UNITED STATES PATENT OFFICE.

JOHN WUNDER, OF SANDUSKY, OHIO.

DESIGN FOR A POISON-BOTTLE.

44,228.

Specification for Design.

Patented June 17, 1913.

Application filed April 19, 1913. Serial No. 762,411. Term of patent 14 years.

To all whom it may concern:

Be it known that I, JOHN WUNDER, a citizen of the United States, residing at Sandusky, in the county of Erie and State of Ohio, have invented a new, original, and ornamental Design for Poison - Bottles, of which the following is a specification, reference being had to the accompanying drawing, forming part thereof.

The figure is a perspective view of the bottle illustrating my new design.

I claim:—

The ornamental design for a poison bottle, as shown.

JOHN WUNDER.

Witnesses:

AL. C. LERMANN,
ALBERTA G. BAUMEISTER.
